UNITED STATES PATENT OFFICE.

ROBERT A. FORESMAN, OF ESSINGTON, PENNSYLVANIA, ASSIGNOR TO WESTINGHOUSE ELECTRIC AND MANUFACTURING COMPANY, A CORPORATION OF PENNSYLVANIA.

MECHANICAL STOKER STRUCTURE.

Application filed July 15, 1920. Serial No. 396,378.

This invention relates to stoker structures, and particularly to stokers of the underfeed type wherein rows of tuyères and fuel-feeding retorts are alternately arranged in parallel relation and inclined from the front wall of the furnace to the dump grate. The invention has for an object the provision of a grate surface composed of parts of simple and durable construction which may be readily assembled or replaced without materially disturbing other parts of the grate.

Another object is to provide a grate structure having superior facilities for maintaining uniform combustion of the fuel at the lower end of the grate and adjacent the dump grate. This is accomplished by placing tuyères in the lower ends of the retorts so that air may be passed to the fuel and uniformly distributed over the entire width of the furnace in the vicinity of the dump grate or the area where final combustion of the fuel takes place.

These and other objects are attained by means of a stoker construction embodying the features herein described and illustrated in the drawings accompanying and forming a part hereof, wherein:

Fig. 1 is a longitudinal vertical section through a stoker structure embodying my invention.

Fig. 2 is a plan view of a fragment of the grate of the stoker illustrated in Fig. 1, parts being shown in section taken on line II—II of Fig. 1.

Referring to the drawings, the stoker includes fuel feeding hoppers 5 which may be of any preferred construction. The discharge channels 6 of the hoppers extend beneath the front wall 7 of the furnace and fuel is forced through the channels by means of reciprocating plungers 8 which may be operated in any desired manner. A casting 9 which extends entirely across the width of the furnace serves to support and to align the discharge channels 6 of the fuel hoppers 5 which are arranged in spaced parallel relation, as indicated in Fig. 2. The hopper castings 5 are bolted or otherwise secured to the front casting 9, as by bolts 9', and the hoppers and the front casting are supported upon an I-beam 11 which is mounted upon any suitable foundation such as that indicated at 12.

Spaced from the front support and ex-

tending across the furnace is a rear grate-support casting 13 mounted upon structural frames 14 which may be mounted directly upon the foundations beneath the casting or supported by the side walls of the furnace. The rear casting 13 and the front casting 9 are connected at spaced intervals by means of frames fabricated from commercial shapes.

In the construction illustrated, each frame includes an upper strut 15 and a lower strut 16 formed of angle iron. The ends of the struts are bolted securely to the casting 13 and upper side wall plates 17 and form a connection therefor, which may expand and contract with variations in temperature without danger of damage. Side plates 17 which are formed in sections and which may be made either of cast or plate iron, are bolted to the upper and lower struts and form the side walls of the retorts. Sectional bottom plates 18 are placed across the space between the two adjacent frames and rest upon the struts 16 to which they are bolted. The side and bottom plates form a retort which extends from the discharge channel 13 of the hopper to a point above the casting 13. The casting 13 is so formed that a continuation of the retort bottom extends to the lower end of the grate to be hereinafter described.

Rows of tuyères 19 are mounted upon the sides of adjacent retorts and extend from a point adjacent the front wall of the furnace to the lower end of the grate and overlap a dump grate 21 which extends entirely across the width of the grate and is pivoted to the casting 13 at 22.

Tuyères 23, similar in construction to the tuyères 19, are placed in the lower end of the retort and form, together with the tuyères 19, a continuous grate surface extending across the width of the furnace, through which air from the air box 24 and beneath the grate may pass to the fuel. The casting 13 is provided with an air box 25 which receives air from the box 24 and delivers air to the tuyères resting thereon and through the hollow dump grate. This construction provides a continuous active grate surface over an extensive area adjacent the ash pit and facilitates the combustion of fuel to completion.

Each retort may be provided with a sec-

ondary or auxiliary ram 26 which reciprocates in the lower end of the retort adjacent to the tuyères 23 and which agitates the fuel in the lower portion of the grate. The ram is connected to a driving means, not shown, by means of a connecting rod 27 which extends forwardly and projects through an upper casting.

While I have described and illustrated but one embodiment of my invention, it will be apparent to those skilled in the art that various changes, modifications, additions and omissions may be made in the apparatus described and illustrated without departing from the spirit and scope of my invention as set forth by the appended claims.

What I claim is:

1. In an underfeed stoker, an inclined grate comprising a retort having a bottom downwardly inclined from front to rear, the lower portion of said retort bottom being formed of a plurality of tuyère blocks superimposed one on the other in stepped relation and having tuyère openings for discharging air rearwardly into the retort.

2. In an underfeed stoker, an inclined grate comprising a plurality of inclined banks of tuyères and retorts between adjacent tuyère banks, each retort being of progressively decreasing depth from front to rear, the bottom of each retort being formed at its lower shallow end of a plu-

rality of tuyère blocks superimposed one on the other in stepped relation and having tuyère openings for discharging air rearwardly into the retort.

3. In an underfeed stoker, the combination of a fuel feeding mechanism, an inclined grate and a refuse-discharging mechanism, the inclined grate comprising alternating fuel retorts and downwardly-inclined banks of tuyères, the bottom of each retort being provided adjacent its lower end with a plurality of tuyère blocks superimposed one on the other in stepped relation, the refuse discharging mechanism including a transverse member for supporting the lower end of the grate and supplying air to the tuyère openings.

4. In an underfeed stoker, an inclined grate structure comprising a plurality of tuyère banks alternating with a plurality of retorts having bottoms inclined from front to rear, the lower portion of each of said retort bottoms being formed of a plurality of tuyère blocks superimposed one on the other in stepped relation and having tuyère openings for discharging air rearwardly into the retort.

In testimony whereof, I have hereunto subscribed my name this 13th day of July, 1920.

R. A. FORESMAN.
